129,412

DESIGN FOR AN AMPHIBIAN AIRPLANE OR THE LIKE

Robert J. Nebesar, Orlando, Fla.

Application March 10, 1941, Serial No. 99,482

Term of patent 14 years

To all whom it may concern:

Be it known that I, Robert J. Nebesar, a citizen of Czechoslovakia, residing at Orlando, in the county of Orange, in the State of Florida, have invented a new, original, and ornamental Design for an Amphibian Airplane or the like, of which the following is a specification, reference being had to the accompanying drawing, forming a part thereof.

Figure 1 is a top plan view of an amphibian

airplane or the like, showing my new design;

Figure 2 is a view in front elevation of the airplane shown in Figure 1; and

Figure 3 is a view in side elevation of the airplane shown in Figure 1.

I claim:

The ornamental design for an amphibian airplane or the like, substantially as shown.

ROBERT J. NEBESAR.
